DEL ROY F. FOWLER

PACKING MATERIAL FOR UPHOLSTERY

Filed Oct. 14, 1924

Inventor:

Del Roy F. Fowler

by Francis D. Chambers
his Attorney

UNITED STATES PATENT OFFICE.

DEL ROY F. FOWLER, OF MELROSE PARK, PENNSYLVANIA.

PACKING MATERIAL FOR UPHOLSTERY.

Application filed October 14, 1924. Serial No. 743,515.

To all whom it may concern:

Be it known that I, DEL ROY F. FOWLER, a citizen of the United States of America, and resident of Melrose Park, Montgomery County, State of Pennsylvania, have invented a certain new and useful Improvement in Packing Material for Upholstery, of which the following is a true and exact description, reference being had to the accompanying drawing, which forms a part thereof.

My invention relates to a packing material for use in upholstery and is especially intended for use in stuffing relatively long and narrow pockets such as are commonly used in motor car upholstery. The object of my invention is to provide a strip of folded fibrous batting of a cross section adapted to fill the cross section of such a pocket which will have sufficient tensile strength to prevent the tearing of the packing strip under the strains to which it is subjected in the operation of stuffing the pockets and which will have its other folded edge so secured to the underlying fold as to prevent or minimize the tendency of such folded strips of batting to unduly expand laterally and get out of shape.

The nature of my invention will be best understood as explained in connection with the drawings which is a cross section of a packing strip embodying my invention.

In the drawing, A indicates a strip of paper forming the core of the packing strip. B indicates the central portion of a strip of fibrous batting which lies below the paper strip and B', B², are the edges of the batting strip, the edge B' being folded down over the paper strip and the edge B² being folded down over the edge B'. C indicates a layer of glue on the under side of the strip A which I preferably use to secure the strip A to the underlying layer B and

D indicates a layer of glue which I use to secure the edge of the overlying bat layer B² to the underlying bat layer B', and it is in the use of this glue layer that the essentially novel feature of my invention consists.

As indicated at d and d' the glue layer D permeates the bat layers above and below and effectively counteracts the tendency of the material in the upper bat layers to expand sideways and deform the strip of batting. My packing strips are of the general character of the padding described in my Patent No. 1,332,550 of March 2, 1920, but is distinguished from this old construction and from the modified forms of such padding which have gone into use by the use of the glue layer D impregnating and firmly securing together the edge of layer B² and the underlying layer B'.

Having now described my invention, what I claim as new and desire to secure by Letters Patent, is:

1. A packing for use in stuffing upholstery consisting of a strip of paper in combination with a strip of fibrous batting folded around the paper strip and with one edge folded over the other and a layer of glue directly securing the outer edge of the folded bat to the underlying bat layer and permeating both bat layers.

2. A packing for use in stuffing upholstery consisting of a strip of paper in combination with a strip of fibrous batting folded around the paper strip and having its central portion secured to the under side of the paper strip by glue, said fibrous bat having one edge folded over the other above the paper strip and a layer of glue directly securing the outer edge of the folded bat to the underlying bat layer and permeating both bat layers.

DEL ROY F. FOWLER.
